Watson E. Coleman
Attorney

UNITED STATES PATENT OFFICE.

ELBERT MCKIERNAN, OF FORT MADISON, IOWA.

DRAFT-REGULATOR.

1,352,670.

Specification of Letters Patent. Patented Sept. 14, 1920.

Application filed September 13, 1919. Serial No. 323,536.

To all whom it may concern:

Be it known that I, ELBERT MCKIERNAN, a citizen of the United States, residing at Fort Madison, in the county of Lee and State of Iowa, have invented certain new and useful Improvements in Draft-Regulators, of which the following is a specification, reference being had to the accompanying drawings.

10 This invention relates to certain improvements in draft regulators, and has relation more particularly to a device of this general character particularly designed and adapted for use in connection with a locomotive, and 15 it is the object of the invention to provide a novel and improved device of this general character whereby the area of a locomotive nozzle tip may be readily and conveniently regulated, as may be occasioned by the various 20 grades of the trackway, the differences in tonnage, grades of coal, or thickness of fire, so that a considerable saving of fuel can be effected.

Another object of the invention is to provide 25 a novel and improved device of this general character whereby the desired regulation of the nozzle tip may be effected with convenience and facility by an engineman within the cab.

30 The invention consists in the details of construction and in the combination and arrangement of the several parts of my improved draft regulators whereby certain important advantages are attained and the device rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein is diagrammatically illustrated a draft regulator constructed in accordance with an embodiment of my invention.

As disclosed in the accompanying drawings E denotes the nozzle or exhaust tip as 0 generally employed in locomotive construction, and which is positioned below the petticoat pipe P, positioned in alinement with the stack S.

Extending axially of the nozzle E is a rod 5 1. The rod 1 extends exteriorly of the nozzle E through the top or open end thereof, and

said upper or outer end portion of the rod 1 has suitably affixed thereto the valve member M, in the form of an inverted cone. As the valve member M is moved toward the upper or open end of the nozzle E the area of the upper or open end portion of said nozzle E may be regulated as the necessities of practice may necessitate, and in order to insure the desired draft on the fire to burn the fuel properly to furnish the required amount of steam to operate the engine at all times.

The rod 1 is supported for endwise movement, and is constantly urged upward through the instrumentality of a coil spring encircling the rod 1, and bearing against a stop 3, suitably affixed to the rod 1.

The stop 3 extends laterally of the rod 1 and suitably secured to said extended portion is an extremity of a flexible member 4. The member 4 may consist of a chain or cable, as preferred. The flexible member 4 extends downwardly to the lower or base portion of the nozzle E, and passes under and around a pulley 5, rotatively supported at the inner end of a horizontally disposed pipe or tubular member 6, extending exteriorly of the nozzle E.

C denotes a cylinder suitably supported in the base portion of the smoke box B, and in which is arranged for rectilinear movement a piston 7. The piston 7 is provided with a stem or rod 8, which extends exteriorly of the cylinder C, through a head thereof, and through the pipe or conduit 6 and the lower end of the flexible member 4, is secured to the outer end portion of said rod or stem 8.

A denotes an air line which leads from a valve, (not shown) in the cab of the locomotive, so that an engineman may adjust said valve in a manner whereby air pressure may be employed to move the piston 7 in a direction to draw the valve member M downward toward the upper or open end of the nozzle E, as the occasions of practice may necessitate.

The extent of movement of the piston 7 within the cylinder C is such as to permit the valve member M to be moved downward, so that the upper or larger diameter of the member M will be level with the top or tip of the nozzle.

10 denotes a coil spring encircling the stem or rod 8 and interposed between the piston 7 and the head of the cylinder C

through which the stem or rod 8 extends for regulating the movement of the piston 7.

From the foregoing description it is thought to be obvious that a draft regulator constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice, except as hereinafter claimed.

I claim:

20 In combination with the exhaust nozzle of an engine, a valve member coacting with the discharge end thereof, a rod depending

from the valve member and supported for endwise movement within the nozzle, a stop fixed to the rod, a spring engaging the stop to constantly urge the rod and valve member in a direction away from the nozzle, a cylinder positioned to one side of the exhaust nozzle, a tubular member extending within the nozzle, a piston mounted for rectilinear movement within the cylinder, a rod coacting with the piston and extending exteriorly of the cylinder and within the tubular member, a guide roller carried by the inserted end portion of the tubular member, and a flexible member secured to the stop carried by the first named rod and passing around the guide roller into the tubular member, said flexible member being also secured to the outer end portion of the piston rod.

In testimony whereof I hereunto affix my signature.

ELBERT McKIERNAN.
